[57] CLAIM

The ornamental design for a vented hair brush block or similar article, substantially as shown.

DESCRIPTION

FIG. 1 is a side elevational view of a vented hair brush block showing my new design;

FIG. 2 is a view similar to FIG. 1 but taken in a plane at right angles to the view of FIG. 1;

FIG. 3 is an end view of the left end of FIG. 2;

FIG. 4 is an end view of the right end of FIG. 1;

FIG. 5 is a cross-sectional view taken on line 5—5 of FIG. 1;

FIG. 6 is a cross-sectional view taken on line 6—6 of FIG. 2;

FIG. 7 is a partial cross-sectional view taken on line 7—7 of FIG. 5; and

FIG. 8 is a cross-sectional view taken on line 8—8 of FIG. 5.
